(57) **CLAIM**

The ornamental design for a voice interface device, as shown and described.

DESCRIPTION

This application is related to U.S. patent application Ser. No. 15/592,126 filed May 10, 2017, now U.S. Pat. No. 10,235,997, U.S. patent application Ser. No. 15/592,128 filed May 10, 2017, now U.S. Pat. No. 10,332,516, U.S. patent application Ser. No. 15/593,236 filed May 11, 2017, now U.S. Pat. No. 10,402,450, and U.S. patent application Ser. No. 15/592,137 filed May 10, 2017, each of which is incorporated by reference in its entirety.

FIG. 1 is a front perspective view of a voice interface device showing our new design;

FIG. 2 is a front elevational view thereof;

FIG. 3 is a rear elevational view thereof;

FIG. 4 is a right-side elevational view thereof;

FIG. 5 is a top plan view thereof; and,

FIG. 6 is a bottom plan view thereof.

The broken lines depict portions of the voice interface device that form no part of the claimed design.
